US0D1070038S

(12) **United States Design Patent** (10) **Patent No.:** **US D1,070,038 S**
(45) **Date of Patent:** **** Apr. 8, 2025**

(54) **SINK**

(71) Applicant: **Duravit Aktiengesellschaft**, Hornberg (DE)

(72) Inventor: **Antonio Citterio**, Milan (IT)

(73) Assignee: **Duravit Aktiengesellschaft**, Hornberg (DE)

(**) Term: **15 Years**

(21) Appl. No.: **29/893,508**

(22) Filed: **May 31, 2023**

(30) **Foreign Application Priority Data**

Feb. 9, 2023 (WO) DM/226645

(51) LOC (15) Cl. **23-02**

(52) U.S. Cl.

USPC **D23/287**

(58) **Field of Classification Search**

USPC D23/284, 286-287, 290, 293.1, 308

CPC E03C 1/14; E03C 1/18; A47B 2220/03;

A47B 77/06

See application file for complete search history.

(57) **CLAIM**

The ornamental design for a sink as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of the sink of the present invention.

FIG. 2 is a front elevation of the sink of the present invention.

FIG. 3 is a rear elevation of the sink of the present invention.

FIG. 4 is a right side elevation of the sink of the present invention.

FIG. 5 is a left side elevation of the sink of the present invention.

FIG. 6 is a top view of the sink of the present invention; and,

FIG. 7 is a bottom view of the sink of the present invention.
